UNITED STATES PATENT OFFICE

JOHN J. JAKOSKY, OF LOS ANGELES, AND ALFRED W. KNIGHT, OF SOUTH PASADENA, CALIFORNIA, ASSIGNEES TO INTERNATIONAL PRECIPITATION COMPANY, OF LOS ANGELES, CALIFORNIA, A CORPORATION OF CALIFORNIA

TIME SWITCH

Application filed August 9, 1926. Serial No. 128,090.

This invention relates to a device for automatic interruption of an electrical circuit at a definite time after the circuit is closed or after the device is set in a certain position and particularly to a device of this type which is especially adapted for use in connection with radio receiving sets, electrical phonograph reproducers, or other apparatus employing thermionic tubes.

The main object of the invention is to provide a time switch which may be connected in the energizing circuit of a thermionic tube or tubes and is adapted to cause such circuit to be automatically interrupted after the expiration of a given time, thus preventing waste of electric energy due to failure to otherwise turn off the radio set or other apparatus in which such tube is embodied. In the operation of radio receiving sets and the like, the operator customarily turns on an ordinary electrical switch of the push or pull or other suitable type and it therefore becomes necessary when the operator is through using the set to again operate this switch so as to open the energizing circuit. It frequently occurs that the operator for some reason or other fails to so open the circuit and the tubes are thus permitted to burn unintentionally for long periods, for example, over night, thus resulting in considerable waste of electrical energy and rapid deterioration of the battery (or consumption of electrical power when an A battery eliminator is used) and also deterioration of the tubes. The object of this invention is to eliminate these disadvantages.

A further object of the invention is to provide a device for this purpose which may readily be installed in an ordinary radio receiving set and which is simple and positive in operation.

A further object of the invention is to provide a device which may also be operated to interrupt the circuit at any time before the time of automatic cut-off. A further object of the invention is to provide a circuit opening switch of such a type that at any time before or after operation of the switch to automatically interrupt the circuit, such switch may be easily reset or placed in opera-

tion so as to continue the period during which the circuit is maintained in closed condition while maintaining an uninterrupted connection in circuit during such resetting of the switch.

The device by which these objects are accomplished according to our invention comprises essentially electrical contact means adapted to be connected in the circuit to be controlled; an operating member movable longitudinally in such manner as to break the connection between said contact means at a certain cut-off position in its movement, means for moving said operating member from such cut-off position, means tending to return said operating member to such position, and means for controlling the rate at which said operating member is so returned. The device further comprises in its preferred form additional contact means which are also adapted to be connected in the circuit to be controlled and are so mounted that connection therebetween is interrupted by said operating member when in another cut-off position, means for moving said operating member to said other cut-off position, and releasable retaining means for holding said operating member in such other position. The invention also comprises certain additional features as hereinafter described.

The accompanying drawings illustrate embodiments of our invention and referring thereto:

Fig. 1 is a longitudinal section of one form of switching device; the operating member being shown at one end of its stroke and the circuit interrupted.

Fig. 2 is a similar view with the operating member in an intermediate position, at which time the circuit is established.

Fig. 3 is a transverse section on line 3-3 in Fig. 1.

Fig. 20 is a transverse section on line 20—20 in Fig. 19.

Fig. 21 is a partial vertical section of the same, showing the manner of breaking connection between the contact means.

The form of the invention shown in Figs. 1 to 7 inclusive comprises a cylindrical casing 1 having an end portion 2 provided with a tubular extension 3 forming a bearing opening within which is slidably mounted the tubular stem 4 of operating member 5, said operating member comprising in addition to such stem an outwardly extending flange 6 at the inner end thereof. At the other end of casing 1, an end member 7 is secured in any suitable manner, said end member having an inwardly projecting cylindrical portion 8. A suitable length of soft rubber tubing indicated at 10 is secured at its respective ends in any suitable manner to the flange portion 6 of operating member 5 and the inwardly projecting portion 8 of end member 7 as indicated respectively at 11 and 12. The means for so securing the rubber tubing at each of its ends may, as shown in Fig. 3, comprise a clamping ring or strip 13 placed over the rubber tubing and provided at its ends with up-turned portions 14 through which extends tightening bolt 15 provided with nut 16 so that said upturned portions may be drawn tightly together so as to hold the rubber tightly into a suitable annular recess or depression 17. A coiled or helical compression spring 20 extends within the tubular stem 4 and bears at one end against the head 21 of such stem and at the other end against the inner face of end member 8. Said spring 20 is of such dimensions as to exert an outward

force against the head 21 of said stem of the desired intensity for causing operation thereof as hereinafter described.

Suitable means are provided for controlling the rate at which the operating member is moved by said spring, such means comprising for example a washer or gasket 24 of sponge rubber or other suitable porous resilient material adapted to control the flow of the working fluid, or in this case of air, through a small bleeder opening 25 into the fluid chamber 26 enclosed within rubber tubing 10 and the members 6 and 8. A washer 27 and nut 28 may be provided upon the threaded projection 29 which is secured to or formed integrally with member 8, for the purpose of adjusting the compression of the resilient porous member 24 and thereby controlling the rate of flow of air therethrough for the purpose hereinafter described. Means are also provided for permitting outflow of air from chamber 26 when the operating member is pressed inwardly, such means comprising for example an outwardly opening check valve 42 of any suitable type mounted at the inner end of an air release passage 43 in an inwardly projecting stem 44 and projection 29.

Releasable retaining means are provided for holding the operating member in the position shown in Fig. 1, such means comprising for example, retaining springs 32 shaped as shown in Fig. 5 and mounted in any suitable manner within a central recess 33 in a rotatably mounted button or knob 31, which fits over the outer end of the tubular sleeve 3. Said springs 32 are provided with inwardly bowed portions 34 adapted, when in the position shown in Fig. 5 to extend through openings 35 in tubular bearing portion 3 and engage in a retaining groove 36 in the stem 4 of operating member 5. The tubular bearing portion 3 is also provided with an annular groove 37, which is in line with the openings 35 and is of varying depth, being deepest adjacent said openings and gradually decreasing in depth away from the same in such manner as to practically disappear entirely or be substantially flush with the surface at points 38 mid-way between the openings 35. Such groove is further provided with two recesses 39 equally spaced from the respective openings 35, into which the bowed portions 34 are adapted to fit when knob 31 is turned as hereinafter described. A threaded retaining ring 45 may be screwed on the front end of tubular member 3 and adapted to engage a shoulder 46 on knob 31 so as to hold said knob against outward movement.

The device may be mounted on the panel 48 of the radio set or other apparatus in connection with which the switch is to be used, by drilling a hole in such panel, as at 49, of the proper size to receive the sleeve member

3, and securing the casing to the panel by means of screws 50. It may be noted here that in mounting the device, the screws 50 are put in place and tightened before mounting the knob 31 on sleeve 3. After tightening such screws the knob is fitted over sleeve 3 and slid inwardly until the springs 32 engage in groove 37 after which the retaining ring 45 is screwed on. When the knob is so secured in position it hides the heads of screws 50, thus giving a neat appearance. If it is desired at any time to dismount the device, the retaining ring 45 may be unscrewed, and knob 31 turned to such position that the bowed portions 34 of springs 32 are moved out of groove 37 or to the shallowest portion thereof, as at points 38, when the knob may be readily withdrawn, again exposing screws 50. In order to indicate when the knob 31 is turned to effective retaining position and when it is out of such position, a segmental plate 51 may be mounted on the panel above sleeve 3 and held in position by means of one of the screws 50, as indicated at 50', said plate being provided with suitable markings such as the words "Off" and "On" as shown, for indicating respectively when the knob is in the aforesaid positions. Knob 31 may be recessed as at 52 so as to make room for the head of screw 50' and permit turning of said knob.

Suitable contact means are provided and are so disposed that connection therebetween is broken when operating member 5 is moved to certain positions. Such contact means may comprise two pairs of contact pins 54 and 55 secured to or mounted on cylindrical casing 1 and interiorly thereof, and two contact springs 56 and 57 which are bent into semi-circular shape as shown in Fig. 4 and are also twisted in such manner that the middle portion of each spring lies substantially parallel to the casing so as to permit the same to be secured thereto as by means of bolts 58 and 53 respectively while the end portions thereof, indicated at 59 and 60 respectively, lie in a plane substantially perpendicular to the plane of the middle portion and are adapted to resiliently engage contact pins 54 and 55 respectively. Operating member 5 is provided with a pair of projecting arms or fingers 61 which may be secured thereto in any suitable manner in diametrically opposite positions, said arms being provided with insulating sleeves or coverings 62 at their outer ends and being adapted to engage spring contact portions 59 and 60 in the motion of said operating member so as to move said contact portions out of engagement with contact pins 54 and 55 respectively. The bolts 58 and 53 may project through casing 1, being thoroughly insulated therefrom as indicated at 64 and may be provided with nuts 65 so as to form terminals or binding

posts for connection of the wires of the circuit thereto as shown in Figs. 8 and 9.

Referring to said Figs. 8 and 9 we have shown in the latter figure a diagrammatic representation of a radio receiving set provided with usual arrangements including thermionic tubes 66, 67, and 68, each provided with filament 69, grid 70 and plate 71. The energizing circuit for the filaments of said tubes comprises wires 72 and 73 connected respectively to the two filament terminals of all the thermionic tubes in parallel. The wire 72 is connected to the positive terminal of the A battery, while wire 73 is shown as connected to the usual rheostat 74 whence wire 75 leads to one of the contact terminals such as 53 of the time switch. A wire 76 leads from the other terminal 58 of the time switch to the negative terminal of the A battery. We have also shown the negative B battery terminal as connected to the negative A battery terminal and thence to the filaments of the several thermionic tubes and it will be seen that when the switch is connected in the manner shown, it serves to break connection in both the A and B battery circuits.

The operation of this form of the invention is as follows:

Under normal conditions, when the tubes are de-energized the stem 4 of operating member 5 is in the position indicated in Fig. 1, and with knob 31 turned to the position shown in Fig. 5 the spring 32 engages groove 36 in said stem and holds the same in this position. Also at this time the arrow 46 on knob 31 points to the word "Off" as shown in Fig. 7. When in this position arms 61 on the operating member engage, through insulating means 62, the end portions 59 of contact spring 56 and hold the same out of contact with contact pins 54 so that the energizing circuit is interrupted at this point.

If it is desired to energize the tubes of the radio set or other apparatus in which such tubes are employed, the knob 31 is turned to the position indicated in Fig. 6, at which time the arrow 46 on said knob points to the word "On" on the plate 51. The bowed portions 34 of springs 32 engage in recesses 38 to hold the knob lightly in this position. Due to this removal of such bowed portions from the groove 36 in stem 4, such stem is released and is forced slowly outwardly by spring 20. As the operating member moves outwardly chamber 26 increases in volume and a condition of partial suction is thus created therein until the excess pressure on the outside of the flanged portion 6 of the operating member is sufficient to balance the force exerted by spring 20. Air is however slowly admitted to chamber 26 through the inlet opening 25, the rate of admission of such air being controlled by the degree of compression of the resilient porous washer 24. Such compression may be adjusted by tightening or

loosening nut 28 to the desired point so as to give any desired rate of movement to the operating member 5. As soon as such operating member is started in motion the end portions 59 of contact spring 56 are released and make connection with contact pins 54 thus completing the circuit as follows: From the negative A battery terminal, through wire 76 to contact terminal 58, through contact 10 spring 56, pins 54, casing 1, pins 55, contact spring 57, terminal 53, and wire 75 to the rheostat and thence to the filaments of all the thermionic tubes, whence wire 72 leads to the positive A battery terminal. It is 15 obvious that the B battery circuit will also be completed at the same time.

The circuit will remain completed and the thermionic tubes remain energized uniformly, throughout the entire period of movement of 20 operating member 5 from its initial position until it reaches a position at which the insulating sleeves 62 of the arms 61 engage contact springs 60 so as to move them out of engagement with contact pins 55. When contact 25 is thus broken, the circuit traced above is interrupted, so that if the operator should forget or fail to return the switch to its normally open position, the switch serves to automatically interrupt such circuit after the 30 expiration of a moderate period, thus preventing any appreciable waste of electrical energy and deterioration of tubes and batteries. The length of time which it takes for said operating member to move between 35 these two positions under the action of spring 20 may be controlled as above described by adjustment of nut 28 so that the thermionic tubes may be maintained in energized condition for any desired reasonable period of 40 time. For example in case of radio receiving sets it may be desirable to so adjust nut 28 that the time of operation of the switch will be approximately one hour although if desired it is possible to vary such time between 45 wide limits for example from five minutes or less to two hours or more.

It will be seen also that as the operating member moves outwardly the stem 4 projects further and further beyond the front of knob 50 31 thus giving an indication when the operating member approaches position to engage contact spring 60 and if it is desired to continue the period of operation of the thermionic tubes beyond that for which the switch 55 was initially set it is only necessary for the operator, either before the operating member so engages contact spring 60 or at any other time during the operation of the time switch, to press the stem 4 inwardly to 60 its initial position or to any other desired position. When the operating member is thus pressed inwardly the air is permitted to escape from chamber 26 through check valve 42 and outlet passage 43, while such 65 check valve effectively prevents inflow of air

through such passage at any time. The electrical circuit is maintained in closed condition throughout such re-setting of the switch. After being thus pressed inwardly the operating member will again start to move out at the same rate as before and the circuit will remain closed until it again reaches cut-off position. If desired, in order to assist in determining when to re-set the switch, visual indicating means such as scale 47 in Fig. 8 7 may be provided on stem 4 for indicating the position of the same. Stop means are provided for the operating member, such means comprising for example a shoulder 63 on end member 2, against which the flange 6 is 8 adapted to come to rest a suitable time after the arms 61 engage contact spring 57.

While the time switch is adapted to interrupt the circuit at a given time after being set in operation, it may be desirable in some 8 cases to break the circuit before the expiration of that time and in such case it is only necessary to turn knob 31 back to its original position as shown in Figs. 5 and 7, at which time the arrow 46 points to the word "Off" 9 and the bowed portions 34 of springs 32 engage openings 35 in sleeve 3. If stem 4 is then pressed inwardly to its original position the spring 32 will again engage groove 36 therein and hold it in this position, thus restoring the switching device to its normal open condition.

A modified form of the invention is shown in Figs. 10 to 14 inclusive. In this form of the invention a metallic cylindrical casing 80 1 is provided which is closed at one end as at 81 and is connected at its other end to a head member 82 of suitable insulating material. Contact springs 83 and 84 are mounted at the respective ends of said casing, the spring 83 1 being insulated therefrom as indicated at 85 and the spring 84 being mounted on insulating head member 83. Said springs are adapted to resiliently engage shoulders 86 and 87 1 respectively on casing 80 so as to make contact therewith. The device may be mounted on the radio or other panel 48 as before, by means of screws 88 which extend through said panel and through or into insulating head member 82. A metallic sleeve or tubular bearing 89 may be threadedly mounted on head member 82 so as to project through a suitable opening 90 in the panel 48. Said sleeve is provided with an opening 91 and an annular groove 92 in line therewith for the purpose hereinafter described.

The operating member 5 may in this case comprise a stem 4, at the inner end of which is secured or formed a flange 94 on which is mounted a leather washer 95 adapted to tightly engage the inside of casing 80 in such manner as to make a substantially air-tight fit therewith. Such washer may be clamped between flange 94 and a retaining ring 96 by means of screws 97, and a spreading mem-

ber 98 of light spring brass or other suitable material may be also clamped between said members for assisting in holding the washer 95 outwardly against the casing 80. Said spreading member may advantageously be slotted in the usual manner of such devices as indicated in Fig. 10. An insulating member 99 is also mounted on the operating member 5 in position to engage contact springs 84 10 at the outer end of the stroke of such operating member as hereinafter described.

A stem member 101 may be provided which is threaded at its outer end as at 102 so as to receive nuts 103 which hold said stem member 18 in position and also serve for connection of one of the wires of the circuit thereto. Suitable means such as leather washers 104 are provided for making an air tight fit around said stem member. The inner end of said 20 stem member serves to guide the compression spring 20 which as before engages the end 21 of stem 4 and engages at its other end a shoulder 105 on stem member 101. Suitable means are also provided in this case for controlling 28 the rate of admission of air to chamber 26 between the leather washer 95 and the end member 81, such means comprising, for example, screw 107, washer 108, and sponge rubber washer 109, which controls the flow 30 of air through inlet opening 110.

The contact spring 84 may be mounted on insulating head member 82 by means of bolt 111, which is set in a recessed portion of said head member, and nut 111'; and a terminal 35 bolt 112 may also be set in such recessed portion and extend through the insulating head member 82 and may extend through and be insulated from a flange 80' on casing 80 and provided at its outer end with nuts 113 for 40 connection of the other wire of the circuit thereto. The bolts 111 and 112 may be connected by means of wire 114.

Suitable means are also provided in this case for releasably retaining the operating 45 member in the position shown in Fig. 10, such means comprising for example a knob 115 provided with a retaining spring 116 formed as shown in Fig. 14 and provided with an inwardly projecting portion 117 adapted 50 when in the position shown in such figure to project through the opening 91 and engage in the groove 36 in stem member 4. Retaining spring 116 is also bent back at one end as at 118 so as to engage in groove 92 and in 55 said spring engages throughout a considerable portion of its length in an annular recess 119 in knob 115 in such manner that engagement of spring 116 in groove 92 and in recess 119 serves to hold the knob on sleeve 60 89. The other end of spring 116 is bent over and engages a hole 120 in knob 115 so as to cause said spring to be turned with said knob.

In the operation of this form of the invention it will be seen that as long as the operating member is in any intermediate position

such as shown in Fig. 11, the electrical circuit is completed as follows: From terminal 102 through contact spring 83, shoulder 86, casing 80, shoulder 87, contact spring 84, bolt 111, wire 114, to terminal bolt 112. When, however, stem 4 is pushed inwardly to position shown in Fig. 10 with the knob 115 turned to the position shown in Fig. 14, the inwardly projecting portion 117 of spring 116 engages in groove 36 and holds said stem in this 70 position. It will be seen that at this time the flange 94 of operating member 95 engages contact spring 83 to hold the same away from shoulder 86 so that the electrical circuit is interrupted at this point. If knob 115 is 80 turned to any other position the projecting portion 117 is raised out of opening 91 into the groove 92, thus releasing stem 4 and permitting the operating member to be moved outwardly by means of spring 20. Suitable means may be provided for indicating the "On" and "Off" positions of the knob 115. Due to the air-tight fit of washer 98 against casing 80 a condition of partial suction is as 85 before created in chamber 26 and the operating member is thus permitted to move outwardly only as fast as air is admitted through controlling means 109. When the operating member reaches the outer end of its stroke the insulating portion 99 thereon engages contact spring 84 and moves the same away from 90 its position of engagement with shoulder 87 thus again breaking the connection at this point. If desired, in order to give a quick motion to the operating member at the end of its stroke and thus enable it to more readily operate contact spring 84, a small opening 122 may be provided in casing 80 in such position that washer 98 passes said opening slightly before the operating member reaches 95 the end of its stroke. When said washer passes said opening, air is suddenly admitted therethrough to chamber 26, so that the remaining movement of the operating member takes place rapidly, thus ensuring positive 100 operation of spring 84. Member 99 may be provided with a portion 100 which is adapted to engage stop means 122 on end member 82 and limit the outward movement of operating member 5 so as to prevent injury of 105 contact spring 84. The operating member may as before be pressed inwardly at any time, in order to continue the period of operation thereof, and may again be restored to normal position to open the circuit at any 110 time by turning the knob 115 back to the position shown in Fig. 14 and again pressing stem 4 inwardly to its original position.

A simpler form of the invention is shown in Figs. 15 to 17. The device shown in these 115 figures comprises a cylindrical casing 125 closed at both ends as at 126 and 127 and having a tubular sleeve or bearing portion 128 at one end in which is slidably mounted the stem 129 of operating member 5. Said oper- 120

ating member comprises in addition to the stem 129, a cup-shaped member 130 mounted at the inner end of said stem and carrying a leather washer 131 which is adapted to make an air-tight fit with the inside of casing 125. The member 130 may be mounted on stem 129 in any suitable manner, for example, it may be held against a shoulder 132 on said stem by means of an insulating nut 133. A sponge rubber washer 134 may advantageously be placed under the nut 133 and the shoulder portion 132 may be provided with an air-passage 135 in such manner that tightening of nut 133 compresses the sponge rubber washer 134 to any desired degree and hence controls the rate of air flow through passage 135.

The sleeve 128 may be adapted to fit in a suitable hole or opening in the panel 48 as shown and may be threaded at its outer end to receive a retaining nut 137 which serves to mount the device on the panel. Compression spring 138 is provided inside casing 125 and engaging the inner end of operating member 5 so as to tend to force the same toward the left in Fig. 16. The stem 129 may be provided at its outer end with a suitable handle or button 139 by means of which the stem may be drawn out to the desired position and said stem may be provided with scale means as indicated at 140 for indicating the position of said stem. Such scale means may be graduated in any desired manner for example as shown in Fig. 15 it may advantageously be calibrated to read in terms of minutes and hours of operation so that the extent to which stem 129 is pulled out in any case will depend upon the desired time of operation.

At the inner end of casing 125 contact springs 142 and 143 are provided, such contact springs being mounted for example on end member 126 by means of terminal bolts 144 and nuts 145 and being completely insulated therefrom as indicated at 146. Said contact springs are provided respectively with contact points 147 and 148 which are adapted under the resilient action of said contact springs to engage one another so as to close connection between the wires 75 and 76, which may be connected respectively to contact members 142 and 143 in such manner that when the nut 133 is withdrawn from between the contact springs the electrical circuit is established. Therefore when it is desired to turn the switch on, the button 139 is pulled out until the desired period of operation is indicated on scale means 140, whereupon the electrical circuit is established. The stem is then released and is slowly forced inwardly by spring 138. The resulting compression of air in chamber 26 between washer 131 and end member 136 creates an excess pressure on the outside of such washer and cup-shaped member 130, which opposes the action of the spring, thereby causing the operating member to return very slowly to its

initial position. It will be understood that in assembling the device the nut 133 is so adjusted as to compress sponge rubber washer 134 sufficiently to permit the desired rate of leakage of air through passage 135 and hence the desired rate of operation of the operating member. When said operating member reaches the end of its stroke or the position shown in Fig. 17, the contact springs are spread apart as there shown, thus interrupting the circuit. With this form of the invention, as in the forms above described, if it is desired to continue the period during which the circuit is completed beyond the time for which the switching device is initially set it is only necessary at any time before completion of the operation thereof to again draw the same outwardly to any desired position, and it will be seen that the electrical circuit is maintained closed during such resetting operation.

Another simple form of the invention is shown in Figs. 18 to 21 inclusive. It is believed that this form of the invention is so similar in general construction to the forms shown in Figs. 10 to 14 inclusive as to require no detailed description. The operating member comprises as in such other form of the invention a stem 4 and leather washer 95, and compression spring 20 tends to force said stem outwardly. The inflow of air to chamber 26 is in this case controlled by a small needle valve 153 mounted at one end of the cylinder 80 and communicating for example with the inside of hollow stem 154 which is open at its other end so as to provide communication with chamber 126. A sleeve 155 at the end of casing 80 is in this case inserted through an opening in the panel and a retaining nut 156 is screwed onto the end of said sleeve.

The contact means in this form of the invention comprises a contact point 158 formed or mounted upon a laterally projecting portion 159 of the casing and another contact point 160 on contact spring 161 which is mounted on and insulated from said laterally extending portion 159 for example by means of terminal bolt 162. Another terminal bolt 166 is provided on the casing or the lateral extension 159 thereof for connection of the other wire of the circuit thereto. Contact spring 161 is provided at its end with an insulating portion 163 which is adapted to be engaged by shoulder or projection 164 on stem 4 when the same reaches a certain position in its stroke. A shoulder or stop member 165 may be provided at the end of casing 80 against which the shoulder 164 is adapted to engage shortly after engaging the insulating portion 163 on stem 161 and moving the same to open position to break connection between contact points 158 and 160 as shown in Fig. 21. The stem 4 is also shown in this case as pro-

vided with scale means 140 calibrated in terms of time of operation. A band 167 of distinguishing color, for example red or white, may also be provided on stem 4, in such position as to come into view slightly before the contact is broken, thus furnishing a warning of this fact so that the switch may be reset if desired.

Under normal conditions when the circuit is not to be energized the operating member is in the position shown in Fig. 21 so that the electrical circuit is interrupted between contact points 158 and 160. When it is desired to establish the circuit the stem member 4 is pressed inwardly until the desired time of operation is indicated on the scale means with which said stem is provided. Contact is thereby established between contact members 158 and 160, thus completing the circuit and such circuit remains so completed until the operating member is forced by spring 20 into its original position, the rate of return of such operating member being so controlled by the flow of air through needle valve 153.

While we have particularly described the use of air as a working fluid for controlling the rate of operation of our switching device, it will be understood that any suitable fluid may be employed for this purpose. The device comprises, in any case, means defining a substantially fluid-tight leather washer sliding in a cylinder or a length of rubber tubing closed at both ends, an operating member having a portion forming a part of the wall of said chamber and movable so as to vary the volume of said chamber, means acting on the operating member to move the same, means for controlling fluid passage into or out of said chamber upon change in volume thereof, and contact means as above described controlled by said operating member.

We claim:

1. A time switch comprising, in combination with an electric circuit, contact means included in said circuit and operable to break the same at either of two points, an operating member operable to first cause operation of said contact means to close the circuit at one of said points while said circuit is closed at the other point and, at a predetermined time thereafter, to cause operation of said contact means to break the circuit at the other of said points, and manually releasable means for holding said operating member in a position of engagement with said contact means such as to cause the circuit to be held open at said one point.
2. A time switch as set forth in claim 1, said operating member being manually returnable to said position of engagement with said contact means at any time after release of said holding means.

In testimony whereof we have hereunto subscribed our names this 31st day of July, 1926.

JOHN J. JAKOSKY.
ALFRED W. KNIGHT.
